QUICK-ACTING LAUNCHING DEVICE FOR
BOATS AND THE LIKE

Harrison C. Hartzog, Port Lavaca, Tex.

Application May 14, 1942, Serial No. 442,969

5 Claims. (Cl. 9—22)

This invention relates to a launching device for boats and the like, and has for one of its objects the production of a simple and efficient means for facilitating the launching of beach landing boats, submarine chasers, life-boats, sailing launches and small boats of any character, from a carrier of any type such as a war or merchant ship.

A further object of this invention is the production of a simple and efficient launching device which may be supported at the side of a carrier ship, and which may be operated in a manner to instantaneously and safely swing a small boat well away from the sides of a carrier ship and deposit the small boat upon the surface of the water where the small boat may be in a position to immediately speed away from the carrier ship toward its target or other objective.

Other objects and advantages of the present invention will appear throughout the following specification and claims.

In the drawings:

Figure 1 is an edge elevational view of the launching device in a retracted position;

Figure 2 is a side elevational view of the launching device in a retracted position;

Figure 3 is a perspective view of the launching device in a retracted position;

Figure 4 is an edge elevational view showing the launching device in an extended or boat-discharging position;

Figure 5 is an edge elevational view of a modified form, the parts being shown in a retracted position;

Figure 6 is an edge elevational view of a modified type of launching device wherein the upper end thereof is substantially flush with a supporting deck;

Figure 7 is a fragmentary perspective view of a boat cradle having a check means suspended therefrom;

Figure 8 is a fragmentary edge elevational view of a boat-releasing device and check carried by the cradle; and

Figure 9 is a vertical sectional view taken on line 9—9 of Figure 8.

By referring to the drawings, it will be seen that A designates a supporting or carrier ship of any type which supports a supporting frame 10 in a manner whereby the frame 10 may be removed from the ship's side when desired. In the form shown, the frame 10 is provided with retaining hooks 11 which fit in suitable receiving apertures formed in the deck of the carrier ship

so that the frame 10 may be removed when and if desired. It should be understood that the frame 10 may be hung from a dock or other support without departing from the spirit of the invention.

The frame 10 preferably comprises an elongated vertically extending structure having an upper transverse horizontal bar 9 and a lower transverse bar 12 connected by two vertical side bars or rails 13. An intermediate transverse horizontal bar 14 is located just above the lower bar 12. A lower U-shaped yoke 15 is hinged to the lower bar 12, and an upper U-shaped yoke 16 is hinged to the intermediate bar 14. The outer ends of the yokes 15 and 16 are hingedly connected in proper spaced relation to a vertical boat-carrying frame 17 in a manner to swing the frame 17 downwardly and outwardly away from the supporting frame 10 when the frame 17 is released. The frame 17 carries boat cradle arms 18 which project outwardly of the frame 17 and are adapted to releasably support a boat B. A suitable latch of any desired type is carried by the frame 10 and is adapted to engage the frame 17 to releasably hold the frame 17 in a retracted position. In the drawing a conventional hook 19 is illustrated for this purpose. A suitable cable and grapple 20 may be employed to raise the frame 17 to a retracted position after the boat B has been launched or when it may be desired to do so.

In order to break the fall of the boat B and cushion the contact of the boat B with the water while launching, damper plates 21 of suitable character are carried by the bottom yoke 15 upon suitable supporting rods 22. These plates 21 may be of suitable size and shape in proportion to the weight of the frame 17 and boat B to constitute a proper damper to check the force of contact of the bottom of the boat with the water in which the boat B is being launched before the boat B contacts the water.

In Figure 5 there is shown a modified form wherein the supporting frame 10a carries a boat-carrying frame 17a in a manner similar to the structure above described, but a suitable check 23 engages the two frames to provide a check or damper to retard the outward swing of the frame 17a relative to the frame 10a. The check 23 is provided with suitable bleeder openings 23a at the opposite ends thereof.

In Figure 6 there is illustrated a modified form wherein a supporting frame 10b is carried by a carrier ship C, the upper end of the frame 10b extending substantially flush with the deck of

the carrier ship C. The boat-carrying frame 17^b is hinged to and carried by the frame 10^b in a manner previously described relative to the previous figures in the drawings.

Various forms of checks may be provided to retard the fall or smashing contact of the boat with the water while launching. In Figure 7 one form of structure is illustrated embodying a hanger 24 which is suspended from the cradle arms 18^a which arms are carried by the frame 25. The frame 25 is similar to the boat-carrying frame 17. An apertured bridge 26 is supported between the hanger 24 below the arms 18^a to check the fall of the boat which is adapted to be carried by the arms 18^a as the frame 25 swings to a launching position.

In the form shown in Figure 6, the cradle 18^b is supported approximately flush with the deck of the ship C, so that the boat to be launched may be easily moved from a position on deck to a position upon the cradle 18^b. In fact, the parts may be so mounted as to permit the launching of a series of boats one after another, from the same launching device simply by moving one boat from the deck to the cradle, then launching the boat, then raising the launching device to receive a second boat and other boats in sequence, until the entire series of boats have been launched.

A further form of check is illustrated in Figures 8 and 9, wherein a hanger 26 is suspended below the cradle arms 27. Damper plates 28 are carried by the bottom of the hanger 26, and one of these plates 28 is apertured, as at 29. This aperture is normally closed by means of an upwardly opening gate valve 30. This valve 30 actuates a pull rod 31 which in turn operates a bell crank lever 32. The lever 32 is pivoted upon the cradle 27, and is connected to a pull pin 33 which extends through an apertured plate 34 secured to the bottom of the boat D. As the plates 28 strike the water in which the boat D is to be launched, the water will force the gate valve 30 open thereby extracting the pin 33 from the apertured plate 34 and thereby automatically unlocking the boat D from the cradle arm 27.

Before launching the boat B, the engine is warmed-up and running, and is properly manned so that at the instant the boat B strikes the water upon launching, the boat B may get underway and speed at once toward its objective and away from the carrier ship A, thereby avoiding danger of crashing against the carrier ship. In launching the boat B, the frame 17 is released at the proper time with regard to the action of the water to reduce the danger of crashing to a minimum.

Having described the invention, what I claim is:

1. A launching device of the class described comprising a supporting frame, adapted to be carried by a support such as a carrier, ship, dock, and the like, a boat-carrying frame hinged near the lower end of the supporting frame and being adapted to swing downwardly and away from said supporting frame to a boat-discharging position for quickly depositing a boat carried thereby upon the surface of the water beyond the support, and damper plates carried by the boat-carrying frame for contacting the water in which the boat is to be launched prior to the contact 70

of the boat with the water to check the fall of the boat-carrying frame and protect the launched boat from injury.

2. A launching device of the class described comprising a supporting frame adapted to be carried by a support such as a carrier ship, dock, and the like, a boat-carrying frame hinged near the lower end of the supporting frame and being adapted to swing downwardly and away from said supporting frame to a boat-discharging position for quickly depositing a boat carried thereby upon the surface of the water beyond the support, damper plates carried by the boat-carrying frame for contacting the water in which the boat is to be launched prior to the contact of the boat with the water to check the fall of the boat-carrying frame and protect the launched boat from injury, and means operable by said damper plates for automatically releasing a boat carried by the boat-carrying frame when said plates contact the water.

3. A launching device of the class described comprising a supporting frame, a boat-carrying frame hinged to the supporting frame and adapted to swing outwardly away from the supporting frame, means for releasably holding the boat-carrying frame in a retracted position and being adapted to permit said boat-carrying frame to swing outwardly and away from the supporting frame when released for quickly and safely placing a boat upon the surface of water beyond the side of the supporting frame, and a boat-carrying cradle carried by the boat-carrying frame, the boat-carrying frame rigidly supporting said cradle at all times to hold the boat in a substantially horizontal plane against independent swinging movement with respect to the boat-carrying frame as the boat-carrying frame is swung outwardly.

4. A launching device of the class described comprising a supporting frame, a boat-carrying frame mounted to rigidly support a boat to be launched, and superimposed yoke frames hingedly connecting the boat-carrying frame with the supporting frame for swinging the boat-carrying frame outwardly, downwardly and away from the supporting frame and holding the boat-carrying frame in vertical parallel relation with said supporting frame at all times during the swinging movement of the boat-carrying frame, and boat-engaging means carried by the boat-carrying frame for holding a boat upon the boat-carrying frame against independent swinging movement as the boat-carrying frame is swung outwardly.

5. A launching device of the class described comprising a supporting frame adapted to be carried by a support such as a carrier ship, dock, and the like, a boat-carrying frame hinged near the lower end of the supporting frame and being adapted to swing downwardly and away from said supporting frame to a boat-discharging position for quickly depositing a boat carried thereby upon the surface of the water beyond the support, and check means adapted to contact the water in which the boat is to be launched to check the fall of the boat and protect the launched boat from injury.

HARRISON C. HARTZOG.
